UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed July 10, 1924. Serial No. 725,129.

This invention relates to manifolding upon fan-fold paper work-webs in typewriting machines, particularly those having revoluble platens.

5 The usual practice in such types of machines is to locate individual sheets of carbon between the plies or folds of the web in a manner which calls for straightening out the web at frequent intervals to permit 10 the shifting of the carbon-sheets along the web from the typed portion thereof to the untyped portion of the same. An occasional incident to such shifting of the carbon-sheets has been the maladjustment of individual 15 carbon-sheets relatively to others between the plies of said web.

In order to overcome the foregoing drawback of shifting the carbon-sheets, as is now found necessary in the present marketed Underwood fan-fold machine, the 20 present mechanism is provided, which is primarily designed to simplify construction in a manner that renders unnecessary the raising of the platen for the straightening 25 of the web, or shifting the same to release the carbon-sheets from contact with the plies of the web.

Another object of the invention is to provide means for automatically or manually 30 measuring predetermined uniform lengths of the web as the same, after being printed, is progressively carried beyond the platen in order to assure that these predetermined typed portions of the web may correspond 35 to the length of the printed forms on the web prior to severing them from the untyped portions thereof.

A still further object of the invention is to provide various economies in the construction and operation of a mechanism designed to produce simultaneously typed impressions upon the several plies of a fan-fold web, looking towards the ultimate separation of each member of a series of forms 45 printed consecutively upon said web.

It is a still further object of the invention to attain the above-named results by the aid of ink-ribbons instead of carbon-sheets as the manifolding medium for producing simultaneously typed impressions upon the 50 separate plies of a fan-fold web.

Other features and advantages will hereinafter appear.

In the accompanying drawings, Figure 1 is a cross-sectional elevation of 55 the invention.

Figure 2 is another cross-sectional elevation thereof, showing the ink-ribbons in a different position to that occupied in Figure 1.

Figure 3 is a front elevation of the various parts of the invention.

Figure 4 is a diagrammatic view, partly in section, of the ribbons nested within the 60 plies of a web.

Figure 5 is a view similar to Figure 4, showing a modification of the nested relation between ribbon and web.

Figure 6 is a fragmental top plan view 70 of the ribbon-carrier and supports therefor, showing a cam controlling the action of said carrier.

Figure 7 is a fragmental exaggerated view 75 of a typewriter ribbon engaging an adjacent part of the ribbon-carrier.

Figure 8 is a fragmental section of a typewriter ribbon, showing the manner in which the typed impressions upon said ribbon occupy the major portion of the surface thereof.

Figure 9 is a view similar to Figure 8, carrying further the same idea as concerns using up the greater portion of the surface of the ribbon.

Referring to the drawings, 10 designates 85 the manifolding sheets or strips which are employed in the form of typewriter ribbons, which ribbons are auxiliary to the usual main ribbon found in a typewriter. These stretches of ink-ribbon are arranged to be 90 positioned longitudinally of the machine so as to be disposed at the delivery side of the platen along the printing line. It is contemplated to use as many stretches of ribbon as may be necessary to produce typed impressions upon all the plies of a fan-fold web. The ribbon-carriers are broadly designated 11, and each consists of a longitudinally-extending arm or blade 12 extending 95 co-extensively with the ribbon, which it serves to position and support by means of integral hooks 13 formed upon its opposite

ends, these hooks receiving the loops 15 formed terminally upon the ribbon 10, which ribbon is held against downward displacement from the blades by means of the bills 14 of the hooks. It will be seen that the ribbons are thus removably mounted upon their carriers.

A fan-fold web 10* is preferably employed in the typewriting machine upon which the attachment and invention is mounted, and this web is integrally provided transversely thereof, continuously of its entire length, with alternate folds E and F, providing a series of longitudinal plies designated A, B, C, D, and so forth, said folds being open at alternately opposite ends thereof for the insertion thereinto of the carbon ribbons 10, which ribbons may easily and removably be introduced, one entering from one side 20 of the web and the other from the other side thereof, and so on, so that one loop end of each ribbon 10 will project beyond and outside the folds of the web, the other being encased in one of the folds of the web, as 25 shown clearly in Figures 4 and 5. This results in the free ends of the ribbons and the hooks 13 of the ribbon-carriers being supported in staggered relation with respect to the longitudinal edges of the fan-fold web 30 10*; however, the ink-ribbons 10, which are arranged in longitudinal alignment within the folds of the web, extend throughout the effective transverse area of the web, these 35 ribbons acting as a unit for the purpose of receiving simultaneous strokes from the type-bars 35 of the machine.

16 designates the brackets upon which the ribbon-carriers 11 are detachably secured. 40 17 designates the platen mounted on a shaft 18 in the usual bearings of the machine, having a hand-wheel 19 for revolving the same manually, and also carrying the line-space ratchet-wheel 47. Ears 20 extend preferably integrally and upwardly from the hooked ends of the ribbon-carriers 11, so as to extend laterally outwardly thereof, and are removably secured upon the brackets 16 by binding screws 21, which are provided with the usual nuts. The brackets 16 are 45 mounted upon bracket-pieces 22, which are operatively positioned adjacent the platen-shaft 18 at the opposite sides of the machine, and which bracket-pieces are secured to each other by a cross-bar 22*. The left-hand one 50 of the bracket-pieces 22 carries a pin 23 projecting preferably in a spiral groove 24 or cam surface formed upon a cam 25 carried by the platen-shaft 18, by means of which cam mechanism a horizontal movement is 55 imparted to the ribbon-carriers 11 for a purpose to be hereinafter explained.

The bracket-pieces 22 carry headed studs 27 formed on the pins 23, which project into a diagonal slots 28* formed upon a slotted portion 28 formed upon the depending bear-

ings 26 of a detachable plate 37* on the platen-frame 37. The horizontal movement imparted to the bracket-pieces 22 causes the headed stud 27 to engage in cam fashion the diagonal slots 28*, whereby vertical movement is also imparted and impressed upon the ribbon-carriers, whereby the resultant of this combined vertical and horizontal movement is to give the ink-ribbons a universal play relatively to the printing line of the machine in order to use up practically the whole surface of the ribbons 10. 29 and 30 designate the front and rear feed-rolls, which are retractably engageable with the platen and serve to provide a tensioning means for holding the web in progressive feeding engagement against the platen, so that the web may be carried along over the side of the platen in arched manner, as shown particularly in Figures 1 and 2 at 31.

32 designates a slidable gage mounted upon a shelf-bar or gage-bar 44 which forms a rest for the advancing typed portion of the web just emerging from beyond the printing line of the machine. The gage is locked in adjusted position upon the shelf-bar by the usual thumb-screw 33, and the gage has an abutment or stop 34 for arresting the progress of the approaching end of a typed portion of the web at this point, so as to measure off and set apart a predetermined uniform length of this typed portion of the web. 35 designates the type-bars which operate in the conventional manner against the conventional typewriter ribbon 38, which latter vibrates up and down in front of the platen at the type strokes, and with reference to which the ribbons 10 are auxiliary. The type-bars 35 on impinging upon the main ribbon 38 also make impressions upon the ribbons 10, which shift relatively to the printing types in a manner which will be readily understood. In order to sever or detach each of a number of consecutive forms printed upon said fan-fold web 10* at uniform intervals apart, a cutting means is also employed, consisting of a tearing-off knife 39 which is located immediately above the ribbons and blades, so that the latter may remain in their positions between the folds of the untyped web. A knife-supporting arm 40 may be fixed in position, or the same may be pivotally supported so as to move from the dotted line inoperable position shown in Figure 2 to the full line operable position shown in the same figure. It will also be noticed that the two ribbon-carrying brackets 16 (one at each side of the machine) form a depression therebetween and above the ribbon-carrying arms or hooks 13 in order to enable the web to be severed reasonably close to the printing line of the platen, and it will also be noticed that the blades and hooks are bent in arcuate form circumferentially of the platen, as

shown in Figures 1 and 2, in order to hold the typewriter ribbon closely in contact with the plies of the web, and these latter in contact with the platen. A stop pin 43^a on the 5 knife-supporting arm 40 rests upon a knife carrying arm 43 supported on the platen-frame to cause the knife 39 to occupy its proper position at a point directly below the point where the gage 32 is fixed, so that the 10 web, as it extends between the knife 39, when in operable position, and a point where the gage 32 is located, represents the already typed portion of the form printed upon the web, enabling this portion to be drawn 15 forwardly against the knife so as to be severed therefrom. When the knife is not in use it may be swung out of the way, especially when the ribbon-carriers are being attached or detached from the machine. The 20 cams 25 and cams 28^a are responsible for prolonging the life of each of the lengths of ribbons, causing the type-bars to engage different points vertically and horizontally of the ribbons. The cam mechanism also provides means causing the blades and ribbons 25 to swing forwardly to and fro in a direction universally of the platen, producing eventually the paths of contact of the type-bars upon all of the ribbons designated M and N 30 in Figures 8 and 9, which illustrate the fact that the major portion of the height of the ribbon receives the repeated strokes of the type-bars, enabling the ribbons to be gradually used up all over their area.

35 In operation the web 10^a is lifted up and fed along down over the paper-table 36, passing between the front and rear feed-rolls, and the web being thus progressively fed forward around the under side of the 40 platen 17. Thereupon the ink-ribbon blades 12 may be inserted in alternate directions, as shown in Figure 4, between the plies of the fan-fold web and secured to the platen-frame by means of the brackets 16. The 45 typing then takes place and the web is fed past the ribbons line by line by the usual line-spacing mechanism, which mechanism also times the operation of the cam mechanism. When the typing of a form is completed, the advancing end of a web may be 50 manually drawn up to the gage 32 to measure the length of the form, or the same will take place automatically if the web is properly arched; in any event, when the 55 free end of the web is stopped by the gage, this portion is then torn off after engaging the knife-bar 39, so that the untyped portions of the web will remain snugly in their 60 positions behind and between the typewriter ribbons which are properly nested and sandwiched between these plies. In this way by rotating the platen, the plies of the web may be moved through the spaces between the ribbons 10, and to severing position, and 65 by keeping the platen immovable, these plies

will remain stationary in these spaces so as to be engaged against the ribbons during the typing operation.

In some cases transparent or tissue paper 48, shown in Figure 5, may be used for the 70 fan-fold web, so that two plies H and I may fall between the adjacent ribbon stretches instead of the usual single ply. The ink-ribbon causes a typed impression in this instance to appear upon both plies with which 75 it contacts, and similarly the transparency of the paper will permit the typing to be read after the forms are torn off.

At Figures 1 and 2, it will be seen that the ribbon-carrying arms 11 have their 80 ribbon-attaching bills or fingers 14 slightly curved to conform to the curvature of the platen, so that they may readily be moved up and down, in the web-folds, in front of the platen, by means of the ribbon-carrying frame, which, it will be remembered, is pivoted on the platen-axle. It will further be seen that the arms 12 extend tangentially 85 a short distance away from the platen. If the knife 39 occupied a permanently fixed 90 position during the up-and-down swinging movement of the ribbon-shifting frame, the length of the web from the printing line to the edge of the knife would be increased 95 and decreased slightly due to a bulge which would be created in the web by the ribbon-carrying arms 12 in their lowermost positions. To avoid such bulge in the web, or, in other words, to keep the distance from 100 the printing line to the edge of the knife always the same, the knife is supported upon 105 knife-carrying arms 43, each knife-carrying arm being pivoted on a stud 50 secured to a downward extension 51 of the bracket-plate 37^a. The axes of the studs are in 110 alignment with each other and in alignment with the printing line, so that the knife-carrying arms 43 may be swung about the studs to move the knife toward or away from the platen as the ribbons move up and down 115 respectively.

It will be understood that the bulge created in the web by the ribbon-carrying arms when the ribbons are lowered is too small 120 to have any effect on the gaging of the sheet against the gage 32. Consequently the gage 32 is supported on the gage-bar 44 which is relatively fixed. The cross-bar 22^a, which forms part of the ribbon-carrying frame, is bent back sufficiently so as not to obstruct 125 the path of the web 31 when said ribbon-carrying frame is in its lowermost position, Figure 2.

From the foregoing it will be understood that there is provided means extending into 130 the fold of a fan-fold web from the side thereof to support a copying medium in the form of a strip, which copying medium may be moved lengthwise of the platen to change its printing position, that there is provided 135

- a gage at the front of the platen to measure a stretch of work-web with reference to a knife, which web is fed between the auxiliary ribbons on the typewriter carriage, and
- 5 that there are two supports on each ribbon-carrier over which the ribbons may be sprung so as to be held taut between said supports to overcome any tendency of the ribbons to feed with the work-web.
- 10 Variations may be resorted to within the scope of the invention, and portions of the improvements may be used without others.
- Having thus described my invention, I claim:
- 15 1. In a typewriting machine, in combination, a typewriter frame, a revoluble platen mounted thereupon, means on said frame for carrying a fan-fold web around said platen, a series of typewriter ribbons extending longitudinally of the machine through and transversely of the folds of said web, a series of blades supporting the ribbons and extending the length of the platen and also projecting through the folds of said web, 20 each of said blades being arranged separately to support a ribbon and having means for securing the opposite ends of the ribbon thereon means for removably securing said blades, each at one end only, upon said frame.
- 25 2. A device of the kind described, including a pair of connected movable bracket-members mounted upon the sides of a typewriter-platen-frame, a plurality of blades above the printing line and supported upon said brackets so as to extend between the work-plies longitudinally of the platen, and typewriter-ribbons extending along the several blades and secured respectively upon the opposite ends of the respective blades.
- 30 3. The combination with a platen, of a series of longitudinally-extending blades arranged above the printing line and in staggered relation, each blade supported at one end only, ink-ribbons having their opposite ends supported upon the ends of said blades, and means carried by said blades providing a support for the latter.
- 35 4. In a device as described, the combination of a plurality of blades extending in longitudinal alignment in staggered relation to one another, each blade being formed at opposite ends with depending hooks, typewriter ribbons having terminal loops removably positioned upon said hooks, and ears carried by each blade and forming a means of support therefor upon a typewriter machine.
- 40 5. A device of the kind described, consisting of a plurality of ribbon-carriers, each having a longitudinally-extending blade, integral hooks depending from the opposite ends of each blade for movable insertion into the folds of a fan-fold web, integral ears extending upwardly and outwardly

with respect to said hooks, brackets for movably holding said ears and connected to the frame of a typewriting machine, and typewriter ribbons operatively secured upon said hooks, so as to extend co-extensively with 70 said blades.

6. In a typewriting machine, a frame, a platen-shaft revolvably mounted thereon, a platen on said shaft, cams mounted upon the opposing ends of said shaft, a plurality of longitudinally-extending manifolding typewriter ribbons supported horizontally in front of said platen and separately insertable into the fold of a fan-fold web traveling over said platen, ribbon-carriers extending 75 the length of the platen and arranged above the printing line and having supporting ears arranged at opposite sides on said frame, each of said carriers being adapted to receive the opposite ends of a ribbon on its 80 ears and support the same separately, brackets upon which said carriers are removably secured, and means controlled by said cams and engaging said brackets for imparting a series of successive diagonal 85 movements to said ribbons.

7. In a typewriting machine, a platen mounted therein, a platen shaft, a ribbon, means removably supported at the sides of the machine for removably supporting said 95 ribbon, arms carried by said means, pins operatively carried by said arms and fixed and movable cams engaged simultaneously by said pins to impart a diagonal vibratory movement to said ribbon, said movable cam 100 being actuated by said platen shaft.

8. In a typewriting machine, in combination, a platen shaft, a platen fixedly mounted thereupon, a bracket fixed upon said machine, a cam formed upon said bracket, a cam on said platen shaft, a movable bracket engageable by said last-named cam to impart vertical movement to said last-named bracket, means carried by said movable bracket and engageable with the first-named cam, whereby to impart to said movable bracket a horizontal movement, said combined vertical and horizontal movements causing said movable bracket to vibrate diagonally, typewriter ribbon supports for connecting said supports 115 removably to said movable bracket, and means for supporting the ends of said ribbons removably upon said supports.

9. In a typewriting machine, the combination of a platen around which a folded web 120 may be fed, a copying ribbon disposed between the fold of said web, a platen-frame, and a detachable arm supported only at one side of the web at the front of the platen on said platen-frame, said arm having at each end means to which said ribbon is attached.

10. In a typewriter machine, the combination of a platen around which a folded web 125 may be fed, a copying medium disposed in 130

the fold of said web, a detachable arm supported at the front of the platen above the printing line and extending the length of the platen, the opposite ends of said copying medium being secured to said arm and supported thereby, and an oscillating frame to support said arm at one end only and move it over the platen surface.

11. In a typewriting machine, the combination of a platen around which a folded web may be fed, line-spacing mechanism for said platen, a copying medium disposed in the fold, a detachable arm supported at the front of the platen above the printing line and extending the length of the platen, the opposite ends of said copying medium being secured to said arm and supported thereby, an oscillating frame to support said arm, means actuable by the line-spacing mechanism to actuate said frame to cause the copying medium to move longitudinally of the platen, and guiding means to engage said frame to cause said copying medium to move crosswise of the platen.

12. In a typewriting machine, the combination of a platen around which a folded web may be fed, a copying medium disposed in the fold, a ribbon-carrier supported at the front of the platen, a frame pivoted on the axis of the platen to support said ribbon-carrier to move the ribbon up and down in front of the platen, a knife to sever the web, a frame to support the knife, said frame being pivoted in coincidence with the printing line, so that it may be swung forwardly by the ribbon-carrying frame as the latter is swung forwardly and downwardly, so that the knife may retain its proper relation with respect to the web and also be the proper distance away from the printing line, and a connection between the knife-carrying frame and the ribbon-carrying frame to cause them to move together.

13. In a typewriting machine, the combination of a revoluble platen around which a web comprising several plies may be fed, line-spacing mechanism for said platen, auxiliary ribbons interposed between said plies, a frame to support said ribbons, a knife to sever the web, a frame to support the knife, and means actuable by the line-spacing mechanism to actuate said frames to oscillate the ribbons relatively to the platen and to cause said knife to change its position according to the position of the ribbon-supporting frame.

14. In a typewriting machine, the combination of a platen around which a folded web may be fed, copying mediums interposed between the plies of the web, arms extending into the folds of said web from opposite sides of the machine to support said copying mediums, said arms having extensions or supporting members extending upwardly alongside the plies and together

forming a depression, and a knife arranged between said arms slightly above the bottom of the depression, the depression enabling the plies to be drawn forwardly between said extensions against the knife.

15. In a typewriting machine, the combination of a platen around which a fan-fold work-web may be fed, single-ply copying strips interposed between the plies of said web, carriers for said copying strips, said carriers extending the length of the platen, from opposite sides of the web and into the folds thereof to support the carriers, and means to move the copying strips lengthwise of the platen.

16. The combination with types, a platen, and a platen-frame, of a ribbon-frame movably mounted upon said platen-frame, means for reciprocating said ribbon-frame, a plurality of arms mounted upon one end of said ribbon-frame, a plurality of arms mounted upon the opposite end of said ribbon-frame, each arm supported at one end only and extending along the platen above the printing line, and having pendent fingers at its ends, and lengths of ribbon, one for each arm, each ribbon caught at both ends upon said fingers, each arm with its ribbon being detachable and attachable as a unit upon said ribbon-frame.

17. The combination with types, a platen, and a platen-frame, of a ribbon-frame movably mounted upon said platen-frame, means for reciprocating said ribbon-frame, a plurality of arms mounted upon one end of said ribbon-frame, a plurality of arms mounted upon the opposite end of said ribbon-frame, each arm supported at one end only and extending along the platen above the printing line, and having pendent fingers at its ends, and lengths of ribbon, one for each arm, each ribbon caught at both ends upon said fingers, each arm with its ribbon being detachable and attachable as a unit upon said ribbon-frame, said arms lying close to the platen, and said fingers curving down around the platen at the printing line.

18. The combination with types, a platen, and a platen-frame, of a ribbon-frame movably mounted upon said platen-frame, means for reciprocating said ribbon-frame, a plurality of arms mounted upon one end of said ribbon-frame, a plurality of arms mounted upon the opposite end of said ribbon-frame, each arm supported at one end only and extending along the platen above the printing line, and having pendent fingers at its ends, and lengths of ribbon, one for each arm, each ribbon caught at both ends upon said fingers, each arm with its ribbon being detachable and attachable as a unit upon said ribbon-frame, said arms lying close to the platen, and said fingers curving down around the platen at the printing line, each

- of said arms including an angular extension for attachment, said extensions being outside of the path of movement of the work-web, and a web-severing knife extending 5 along the platen between said extensions.
19. The combination with types, a platen, and a platen-frame, of a ribbon-frame movably mounted upon said platen-frame, means for reciprocating said ribbon-frame, 10 a plurality of arms mounted upon one end of said ribbon-frame, a plurality of arms mounted upon the opposite end of said ribbon-frame, each arm supported at one end only and extending along the platen above 15 the printing line, and having pendent fingers at its ends, and lengths of ribbon, one for each arm, each ribbon caught at both ends upon said fingers, each arm with its ribbon being detachable and attachable as a 20 unit upon said ribbon-frame, said arms lying close to the platen, and said fingers curving down around the platen at the printing line, each of said arms including an angular extension for attachment, said extensions being 25 outside of the path of movement of the work-web, and a web-severing knife extending along the platen between said extensions, said knife mounted on arms pivoted to swing said knife forwardly away from the work-web for convenience in manipulating the 30 same.
20. In a typewriting machine, the combination with types, a platen, and a platen-frame having ends, of a ribbon-frame movably mounted at its ends upon the ends of 35 said platen-frame, a device connected with the platen to be effective at the rotation thereof for reciprocating said ribbon-frame, arms mounted upon opposite ends of said 40 ribbon-frame, each arm supported at one end only and extending along the platen above the printing line, and having pendent fingers at both its ends, and lengths of ribbon, one for each arm, each ribbon caught at both 45 ends upon said fingers.
21. In a typewriting machine, the combination with types, a platen, and a platen-frame having ends, of a ribbon-frame movably mounted at its ends upon the ends of 50 said platen-frame, a device connected with the platen to be effective at the rotation thereof for reciprocating said ribbon-frame, arms mounted upon opposite ends of said 55 ribbon-frame, each arm supported at one end only and extending along the platen above the printing line, and having pendent fingers at both its ends, and lengths of rib-
- bon, one for each arm, each ribbon caught at both ends upon said fingers, said reciprocating device connected to move said ribbon-frame both longitudinally and transversely of the platen. 60
22. In a typewriting machine, in combination, a typewriter frame, a revoluble platen mounted thereupon, means on said frame for carrying a fan-fold web around said platen, a series of typewriter ribbons extending longitudinally of the machine through and transversely of the folds of said web, means for independently supporting each ribbon 70 comprising a series of elements, each formed with parts adapted to receive opposite ends of a ribbon and to support the same, and means for supporting each of said elements at one end on said frame. 75
23. The combination with a platen, of a movable carriage on which the same is mounted, a plurality of ribbons, each of which is provided with loops at its opposite ends, and means for supporting said ribbons 80 separately comprising a series of elements, each of which is formed with two spaced parts adapted to engage the loops of a ribbon, and means for supporting each of said elements at one end on said carriage. 85
24. A device of the kind described, including a pair of connected movable bracket-members mounted upon the sides of a typewriter-platen-frame, a plurality of blades above the printing line adjustably supported 90 upon said brackets so as to extend between the work-plies longitudinally of the platen, and typewriter ribbons extending along the several blades and secured respectively upon the opposite ends of the respective blades. 95
25. The combination with a platen and a movable carriage therefor, of a series of longitudinally-extending blades arranged above the printing line and in staggered relation, each blade being detachably supported at one end only on said carriage, ink-ribbons having their opposite ends supported upon the ends of said blades, and means carried by said blades providing a support for the latter. 100
26. The combination with a platen and a movable carriage therefor, of a series of longitudinally-extending blades arranged above the printing line, ink-ribbons having their opposite ends supported upon the ends 110 of said blades, and means for detachably securing each blade at one end only on said carriage. 115

JOHN WALDHEIM.
